TRUCK BOLSTER

Percy R. Drenning, Baltimore, Md., assignor to
 T. H. Symington & Son, Inc., Baltimore, Md.,
 a corporation of Maryland

Application February 18, 1932, Serial No. 593,853

16 Claims. (Cl. 105—230)

The invention relates to railway car trucks and has special reference to truck bolsters.

The principal object of the invention, generally stated, is to provide a bolster of peculiar and novel construction and in which the component walls, webs and other parts are so designed and related as to eliminate secondary stresses.

It is well known that in the ordinary type of bolster while the compression face may be straight for the major portion of its length there is nevertheless at some point or other an offset which causes secondary strains. Moreover the ordinary type has its tension face continuing from its center outwardly and upwardly in substantially the same plane until it approaches the side frames at which point there is an abrupt neck which causes high secondary stresses due to the abrupt changes in direction.

It is with these facts in view that I have devised the present invention which contemplates the provision of a truck bolster having its upper or compression face adjacent the side walls forming a straight line from the end of the bolster to the center line so as to eliminate the usual offset while still permitting use of a side bearing of given height and which need not be specially constructed.

Another object is to provide a bolster having a reinforcement joining the side bearing seat with the side walls instead of the force being transmitted straight down from the seat to the bottom as is a common plan.

Another important object is to provide a bolster in which the tension face or bottom portion is of unusual design in that the tension face adjacent to the side walls is carried in a continuous line beyond the usual necked in portion adjacent the spring seating portion and to a point beyond the center line of the side frame, the resultant offset portion at the spring seat being amply reinforced against vertical reaction and shear by special means calculated to fulfill the purpose.

Yet another object is to provide a bolster in which there are formed openings in the sides near the center line, the openings being of peculiar configuration and formed of different curves and straight lines so related as to provide reinforcement against secondary stresses adjacent the center line.

Still another object is to provide a bolster in which the cross sectional configuration is such that the metal is concentrated at those localities where it is the most useful, the bolster being capable of being described as comprising a pair of channel beams having their edges joined, the

maximum thickness of metal being at the corners and the connecting or joining portions being relatively thin inasmuch as there is no necessity that they have great strength as the strains are distributed throughout the relatively thick portions. 5

The invention further contemplates minor improvements in design and formation so as to obtain maximum strength and efficiency combined with minimum weight.

An additional object is to provide a bolster of this character which while possessing the advantageous characteristics above pointed out will not be any more expensive or difficult to make than one of ordinary design and which will therefore be a distinct improvement in the art. 10 15

To the attainment of the foregoing and other objects and advantages, the invention preferably consists in the details of construction and the arrangement and combination of parts to be hereinafter more fully described and claimed, and 20 illustrated in the accompanying drawings in which:

Figure 1 is a plan view of a bolster constructed in accordance with the invention, a part of the end being broken away and in horizontal section, 25

Figure 2 is a central vertical longitudinal section,

Figure 3 is a central vertical cross section, the view being taken on the line 3—3 of Figure 1,

Figure 4 is a detail cross sectional view taken 30 on the line 4—4 of Figure 1,

Figure 5 is a cross section taken on the line 5—5 of Figure 1,

Figure 6 is a cross section taken on the line 6—6 of Figure 1,

Figure 7 is a cross section taken on the line 7—7 of Figure 2,

Figure 8 is a cross section taken on the line 8—8 of Figure 2,

Figure 9 is a fragmentary side elevation,

Figure 10 is a fragmentary bottom plan view,

Figure 11 is an end elevation.

Referring more particularly to the drawings I have shown the bolster as comprising a top wall 10, a bottom 11 and sides 12. Logically, the upper portion of the bolster constitutes the compression side while the lower portion constitutes the tension side. At the center of the top there is provided an upstanding circular flange or ring-like member 13 which constitutes a center bearing for receiving a center plate depending from a body bolster, not shown. The flange 13 is braced by means of diagonal ribs 14 which merge therewith and which die out at the side edges of the top wall. Within and concentric with respect 50 55

to the flange 13 is a boss 15 which extends partly above and partly below the top wall and which is formed with a cylindrical opening 16 for the reception of the usual king pin. As is customary in bolster construction the greatest vertical depth is at the center, the height or thickness of the bolster as a whole being decreased gradually toward the ends, which ends are of course intended to be received within the bolster openings 10 in the side frames of a truck and to be supported upon a nest of springs. The side frame and springs are not illustrated as they form no part of the present invention and as numerous variations in the design thereof might be resorted to. 15 A feature of distinct importance is that the top working metal of the bolster lies in a continuous straight line from the very extremity to the transverse center line, the flange 13 and the flat circular area within the confines thereof being raised above the unbroken surface. By this construction it is readily apparent that there are no offsets in the top wall or compression side such as would result in the setting up of secondary strains. However, as it is intended to equip 20 the bolster with side bearings of given height and which may be of more or less standard design, I provide a slightly raised pad or seat portion 17 which is located at the intermediate portion of the bolster or in other words which is 25 spaced inwardly from the sides thereof so as not to interfere with the unbroken or continuous line of the upper corners. This seat portion is apertured at 18 for the reception of whatever securing members are necessarily provided for mounting the side bearings and the metal around these 30 openings is increased in thickness as shown at 19. To brace this seat portion so that strains coming upon it through the side bearings will be properly transmitted to other parts of the bolster, 40 I provide inclined ribs or webs 20 which extend from the top wall downwardly and merge into the sides in contradistinction to any structures wherein simple vertical struts extend between the top and bottom walls. I have found it preferable to transmit the vertical load coming upon 45 the side bearings to the side walls of the bolster rather than to the bottom inasmuch as in this way the strain is better distributed instead of being permitted to concentrate upon any localized area beneath the side bearings. These 50 diagonal webs or ribs are most clearly illustrated in Figure 6 though they are also visible in Figures 1 and 2.

The construction at the center of the bolster 55 involves an upstanding post structure beneath the center bearing and connecting the top and bottom 10 and 11 of the bolster. This so-called post structure preferably comprises a hollow member 21 advantageously elliptical in cross section with the major axis of the ellipse extending longitudinally of the bolster. Webs or struts 22 serving as braces for the side walls of the bolster join with post 21 and extend horizontally transversely of the bolster. These webs prevent any 60 local buckling of the side walls 12. The member 21 is internally reinforced against any buckling by a horizontal web 23, which also serves as a support for the usual king pin, said web being located at the intermediate portion of member 65 21. Ribs 24 which merge into the web 23 and into the sides of the member 21 serve as guides for the end of the usual king pin. The web 23 may be formed centrally with a hole 25 and the bottom of the bolster may also be formed with a 70 hole 26 vertically in line below the hole 25. 75

Where the member 21 joins the bottom 11 of the bolster I preferably provide substantially triangular ribs 27 which merge into the member 21 and into the bottom and which diverge toward the ends of the bolster. To reduce the weight of 5 the member 21 it may have its opposite sides at the ends of its minor axis formed with openings 28 above the web 23 and other openings 29 beneath the same.

The end portion of the bolster is of course intended to be received within the window opening of a truck side frame and it is therefore shown as provided at opposite sides with laterally extending lugs 30 reinforced at their upper and lower ends by diagonal ribs 31 and 31^a. These 15 lugs are intended to cooperate with the inner sides of the column guides for the purpose of maintaining the proper relation between the bolster and the side frames. Any desired means may be provided in association with the bolster 20 for cooperation with the outer side of the side frame or column guides for preventing displacement of the bolster with respect to the side frames in the other direction. This means may conveniently consist of a bolt, not shown, passing 25 through holes 32 in the sides of the bolster and through vertically elongated openings in the column guides, this specific detail being of minor importance in the present instance and, if desired, the outer sides of the end portions of the 30 bolster may be more or less chamfered for instance as disclosed in my co-pending application for Bolster for plankless trucks, filed August 25th, 1931 and given Serial No. 559,289. It might be mentioned in passing that the sides may be 35 formed with holes 33 for the purpose of holding on a fulcrum bracket forming part of whatever brake rigging is used and it is clear that these holes 33 need be provided only at diagonally opposite sides considered in relation to the truck 40 center.

The detailed construction or form of the tension portion of the bolster, that is to say the bottom part, is of considerable importance. It should be noted that the bottom wall 11 is curved 45 at the center of the bolster or beneath the center bearing and member 21 and then extends upwardly to the point 34 where it is necessarily changed in direction to provide the bearing portion 35 which rests upon the truck springs. However, the tension face adjacent to the side walls is carried in a continuous line beyond this neck and to a point beyond the center line of the side frame where it dies out into the side walls as clearly illustrated at 36 in Figures 1 and 2. In 50 doing this, there is created an offset 36^a at the spring seat and this offset portion must, of necessity, be reinforced against vertical reaction and shear and this is accomplished in accordance with the present invention by means of segmental 60 ribs 37 beneath the offset portion and merging into the sides thereof and the seat portion 35, said ribs 37 also serving to provide bearing surfaces for a portion of the supporting springs. Adjacent the very end of the bolster the top wall 65 may be partly cut back as at 38 while the bottom preferably projects slightly beyond the sides as shown at 39 for the purpose of providing bearing surfaces for the supporting springs. Reinforcement at this point may be effected by means 70 of a transverse rib 40 formed on the top of the bottom wall and terminating in inclined portions 41 merging into the sides, these inclined portions also serving to locally reinforce the side walls 12 for preventing said walls from buckling. 75

To reduce the weight of the bolster, the top wall may be formed with an elongated opening 42 extending from adjacent the flange 13 outwardly and the end portion may similarly be formed in its top with an opening 43. Moreover the sides may be formed centrally with openings 43^a and if desired with openings 43^b and the bottom 11 may be formed with a relatively long opening 44, the metal at the edges of all of these openings being preferably thickened to define reinforcing beads.

A very important feature in the construction of this bolster is the disposition of the metal where it has the most utility, namely at the corners or outermost edges. As a consequence the top, bottom and side walls are made thickest where they join one another, these thickened portions being indicated at 45 and 46, respectively, and extending throughout the length of the bolster. Below the inner end portions of the side bearing supporting pads or seats 17 the side walls of the bolster are made relatively thick throughout their height as shown at 47 in Figures 2 and 4 for a comparatively narrow area to compensate for the provision of holes 48 therethrough which are provided for the purpose of mounting in place brake beam safety supports such for instance as are shown in the co-pending application of Thomas H. Symington for Railway car trucks, filed July 31st, 1930, Serial No. 472,116, these supports not being illustrated in the present instance as being unnecessary to a proper understanding of the invention. The lines 49 and 50 in Figure 2 represent where the gradually thickened corner portions at the inside surfaces of the side walls of the bolster die out into the relatively thin central portions of the sides.

As an additional way to reduce the weight of the bolster the sides thereof are formed with elongated openings 51 which extend from points opposite the ends of the major axis of the member 21 to adjacent the thickened portions 47. It is optional to use the opening 43^b which begins at this thickened portion 47 and continues outwardly toward the end of the bolster, the outer end bounded by the face of lug 30. To eliminate secondary stresses in the compression and tension members adjacent to the opening 51, I provide webs 54 and 55 having their inner edges conforming to curves of differing radii 53 and 52, the radius 52 being tangent to the edge formed on the compression side by a projection of line 49, at such a point that downward or upward buckling of the compression member is prevented.

The radius 52 on the tension side is tangent to the edge formed by projection of line 50 at a point outwardly of the point of tangency of the curved bottom face of the tension member 11 and the inclined portion thereof, thus bracing the tension side beyond the point of change in direction of this member. The upper edges of the openings 51 lie along the line 49 while the lower ends coincide with the line 50. As an additional stiffening means I provide a bead 56 which merges into thickened portion 47 at the outer ends of the openings 51, along the upper edges thereof and clear across the central part of the bolster at each side thereof. In other words these beads are continuous at each side. Naturally such ribs or beads, especially as they are provided at the critical locations, will be of great benefit as a reinforcement to the compression side or portion of the bolster.

From the foregoing description and a study of

the drawings it will be apparent that I have thus provided a bolster which will be extremely light in weight but which will at the same time be very strong and durable in view of the various means provided at critical points for taking care of secondary stresses and distributing load strains in such manner that buckling or breaking down at any point or points will be avoided. It is thought that the construction and advantages should be apparent to one skilled in the art without further explanation.

While I have shown and described the preferred embodiment of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the scope of the claims hereunto appended.

Having thus described the invention, I claim:

1. A railway car truck bolster provided with a center bearing adapted for swivelling engagement with the center plate of a body bolster, and having its compression side continuing in an unbroken straight line from each end to the transverse center line, the bolster having only the longitudinal central portion of its bottom necked and having the side portions of its bottom continued in a straight line from adjacent the center to the necked portion.

2. A railway car truck bolster formed at its top with a center bearing and having its compression side continued in a straight line inclining upwardly from each end to the transverse center and having its tension side curved at the center and inclined upwardly toward each end in a straight line beyond the center line of a side frame through which the end portion is adapted to extend, the end having a bottom and sides including upper and lower portions, the lower portions of the sides being offset inwardly with respect to the upper portions thereof.

3. A railway car truck bolster formed at its top with a center bearing and having its compression side continued in a straight line inclining upwardly from each end to the transverse center and having its tension side curved at the center and inclined upwardly toward each end in a straight line beyond the center line of a side frame through which the end portion is adapted to extend, the bottom being necked to define a substantially horizontal spring engaging portion at each end, said spring engaging portion being of less width than the remainder of the bolster end.

4. A railway car truck bolster having its bottom formed with a neck defining a spring seat portion at the end, the tension portion or bottom having its side edges continued in a straight line beyond the neck, the sides of the end portion below said edges being inwardly offset, and means at the sides of said end offsets for reinforcing the end.

5. A railway car truck bolster having its bottom formed with a neck defining a spring seat portion at the end, the tension side being continued in a straight line beyond the neck and defining inward offsets at the sides, and means for reinforcing the end, comprising external vertical ribs extending from the bottom of said end portion to the offsets.

6. A railway car truck bolster having a reduced end portion adapted to be received with-

in the window opening of a side frame, the end portion having its bottom offset inwardly from the sides and having tension members formed as a prolongation of the bottom defining the offset portions.

7. A railway car truck bolster having a reduced end portion adapted to be received within the window opening of a side frame, the bolster having its bottom offset to define said end portion and having tension members formed as a prolongation of the bottom inwardly of the offset portion, said tension members continuing beyond the offset, and reinforcing means on the exterior of the bolster located beneath said tension members.

8. A railway car truck bolster having a reduced end portion adapted to be received within the window opening of a side frame, the bolster having its bottom offset to define said end portion and having tension members formed as a prolongation of the bottom inwardly of the offset portion, said tension members continuing beyond the offset, and reinforcing means located beneath said tension members, said reinforcing means being formed as upstanding segmental ribs located exteriorly of the bolster.

9. A railway car truck bolster having a reduced end portion adapted to be received within the window opening of a side frame, the bolster having its bottom offset to define said end portion and having tension members formed as a prolongation of the bottom inwardly of the offset portion, said tension members continuing beyond the offset, and reinforcing means located beneath said tension members, said reinforcing means being formed as upstanding segmental ribs having their convex sides toward the sides of the bolster and having their edges located at and merging into the edges of the tension members.

10. A railway truck bolster having its bottom inclined upwardly from the center and necked to define a horizontal portion adapted to seat upon springs within the window opening of a side frame, the bolster being formed with tension members continuing as a straight line prolongation of the sides of the bottom beyond the neck, said tension members merging into the sides of the bolster beyond the center line of the truck side frame, said prolongations defining inward offsets at the sides of the horizontal portion.

11. A railway truck bolster having its bottom inclined upwardly from the center and necked to define a horizontal portion adapted to seat upon springs within the window opening of a side frame, the bolster being formed with tension members continuing as a straight line prolongation of the bottom beyond the neck, said tension members merging into the sides of the bolster beyond the center line of the truck side frame, ribs at the edges of said tension members, and segmental ribs on the bottom of said tension members joined to said first named ribs.

12. A railway truck bolster having compression and tension sides and provided with a center bearing adapted for swivelling engagement with the center plate of a body bolster, bolster having its tension side formed at its effective portions or side edges in an unbroken straight line from each end to the transverse center line of the side frame into which the ends extend, said compression side being formed with side bearing mounting seats located inwardly of said effective portions or side edges, and solid transverse triangular webs within the bolster merging into the top and sides beneath said seats.

13. A railway truck bolster provided with a center bearing adapted for swivelling engagement with the center plate of a body bolster, having its compression side formed at its effective portions or side edges in an unbroken straight line from each end to the transverse center line, said compression side being formed with side bearing mounting seats located inwardly of said effective portions or side edges, and means beneath said seats for transmitting loads to the sides of the bolster instead of the bottom, said means merging into the top and sides and terminating above the bottom.

14. A railway car truck bolster including a top, bottom and sides, the bottom being necked to define a horizontal end portion adapted to seat upon springs within the window opening of a side frame, abutment members projecting outwardly from the sides adapted for cooperation with the inner side of a side frame, the upper portions of said end portions being of substantially the same width as the window opening and the lower portions of said end portions being reduced in width, and reinforcing means integral with the bolster at the opposite sides of said reduced portion.

15. A railway car truck bolster including a top, bottom and sides, said bottom having its central portion necked to define a horizontal end portion adapted to seat upon springs within the window opening of a side frame, the sides of the bottom being prolonged as a continuation of the major or unnecked portion thereof and thereby defining outwardly overhanging offsets at the horizontal portion, and reinforcing elements located exteriorly of the necked intermediate portion of the bottom and extending from said horizontal portion into said overhanging offsets.

16. A railway car truck bolster including a top, bottom and sides, laterally extending abutment members projecting from the sides of the bolster, the length of the bolster between said abutment members and each end being adapted to extend through the window opening of a side frame, the sides of the bolster between said abutment members and the ends being arranged in converging relation, the end portions of the bolster having inward offsets, and reinforcing means at the sides of the offsets.

PERCY R. DRENNING.
